US00D876448S

(12) **United States Design Patent** (10) Patent No.: **US D876,448 S**
Li et al. (45) Date of Patent: **** Feb. 25, 2020**

(54) **DISPLAY SCREEN WITH GRAPHICAL USER INTERFACE FOR BIO-PRINTER**

(71) Applicant: **REVOKEK CO., LTD**, Sichuan (CN)

(72) Inventors: **Lin Li**, Sichuan (CN); **Changjiang Liao**, Sichuan (CN); **Wende Jing**, Sichuan (CN)

(73) Assignee: **REVOKEK CO., LTD**, Sichuan (CN)

(**) Term: **15 Years**

(21) Appl. No.: **29/655,751**

(22) Filed: **Jul. 6, 2018**

(51) LOC (12) Cl. **14-04**

(52) U.S. Cl. **USPC** **D14/485**

(57) **CLAIM**

The ornamental design for a display screen with graphical user interface for bio printer, as shown and described.

DESCRIPTION

The FIGURE is a front view of a display screen with graphical user interface for bio printer, showing our new design.

The broken lines showing a display screen and elements of the graphical user interface illustrate portions of the article, and form no part of the claimed design.

1 Claim, 1 Drawing Sheet
